UNITED STATES PATENT OFFICE

142,581

DESIGN FOR AN ELECTRIC LIGHT BOWL

Albert J. D. Ohm, Buffalo, N. Y., assignor to Mar-
kel Electric Products, Inc., Buffalo, N. Y., a cor-
poration of New York

Application April 27, 1945, Serial No. 119,260

Term of patent 14 years

(Cl. D48—16)

To all whom it may concern:

Be it known that I Albert J. D. Ohm, a citizen of the United States, residing at Buffalo, in the county of Erie and State of New York, have invented a new, original, and ornamental Design for Electric Light Bowls, of which the following is a specification, reference being had to the accompanying drawing, forming part thereof.

Figure 1 is a perspective view from below of an electric light bowl showing my new design.

Figure 2 is a bottom plan view of the same.

The dominant features of my design reside in the surface ornamentation on the light bowl as shown.

I claim:

The ornamental design for an electric light bowl, as shown and described.

ALBERT J. D. OHM.
